UNITED STATES PATENT OFFICE.

WALLACE WHITE, OF LAWRENCE, MASSACHUSETTS.

PULP-BEATER.

SPECIFICATION forming part of Letters Patent No. 766,563, dated August 2, 1904.

Application filed February 11, 1904. Serial No. 193,038. (No model.)

To all whom it may concern:

Be it known that I, WALLACE WHITE, of Lawrence, county of Essex, State of Massachusetts, have invented an Improvement in

5 Pulp-Beaters, of which the following description, in connection with the accompanying drawings, is a specification, like characters on the drawings representing like parts.

When the beaten pulp and water is drained 10 from a pulp-beater, a large proportion of the pulp is left on the bottom of the tub, which is usually pushed into its outlet with scrapers or washed out with a hose-pipe or by letting water into the tub from a hydrant. This operation takes considerable time and causes a 15 corresponding delay in the operation of the machine. Furthermore, in the well-known horizontal form of beater in general use having the central vertical mid-feather it is necessary to stir the pulp frequently in order 20 that the pulp may be beaten evenly; otherwise the portion of the pulp next the mid-feather would be beaten more rapidly than that next the sides of the tub.

25 My invention has for its object to provide a means for rapidly and thoroughly washing out the tub and removing all the pulp therefrom and rendering the use of scrapers and like devices unnecessary and incidentally to 30 provide a means whereby the speed of the flow of the portion of the pulp adjacent the walls of the tub may be accelerated and the pulp washed during the process of beating, so that the necessity of stirring the pulp continually is to a great extent avoided and the 35 rapidity of the beating process greatly facilitated. I accomplish this object by providing in the walls of the tub adjacent its bottom a series of nozzles which are adapted and arranged to direct a jet of water horizontally in any direction within an angle of one hundred and eighty degrees.

40 For an understanding of the particular means which I preferably employ in carrying out the above object I will now refer to the accompanying drawings, in which—

45 Figure 1 is a plan view of a beating-engine of the ordinary type provided with my invention. Fig. 2 is a detached side view of one 50 of the nozzle-casings. Fig. 3 is a central ver-

tical section thereof. Fig. 4 is a horizontal section on the line xx of Fig. 2. Fig. 5 is a section on the line yy of Fig. 2.

The tub of the beating-engine illustrated has the usual parallel side walls a , semicircular end walls, and an intermediate mid-feather b , with the roll c in the usual position. A series of casings or chambers d are secured to the sides of the tub adjacent the bottom thereof, one being located at each end of the straight portion of each of the two side walls, as shown in Fig. 1, although they may be arranged in different positions and their number be varied without departing from the spirit of my invention. 65

A main water-supply pipe leads to a supply-chamber e , which is located below the bottom of the tub and centrally thereof, as indicated in dotted lines, Fig. 1, and branch pipes f lead from said chamber e to each chamber d , so that an approximately equal volume of water may be supplied to each chamber d . 70

As the parts contained in each chamber d are identical, a single description will suffice for all. Each chamber d is connected to the interior of the tub by a circular passage d' , the lower portion of which extends as closely as practicable to the upper edge of the usual filling-strip a' in the corner of the tub. The inner end of the passage d' is beveled or made 80 flaring, as indicated at a'' , and a packing-ring g is secured to the outer side of the tub about said passage to form a water-tight joint therebetween. Said packing-ring is provided with a beveled face adapted to form a water-tight 85 seat for the face of a spherical valve or nozzle h . Said nozzle is hollow and is provided with a discharge-port h' of oblong form, the sides thereof being parallel and its ends semicircular and so arranged that 90 a horizontal plane through the geometrical center of the sphere passes through the center of said port perpendicular to its sides. Two inlet-ports h'' are also provided in the opposite side of the nozzle or shell h from 95 port h' , said ports h'' being separated by a horizontal bridge h^3 , the center of which is in the horizontal plane through the center of the shell. Two bosses h^4 are formed on the inner surface of the shell h at diametrically 100

- opposite points, each having an oblong or other shaped aperture having different diameters formed therethrough in alinement, and a correspondingly - shaped stem *i* passes through said apertures and through a stuffing-box *b*' in the upper side of the casing *d*, a hand-wheel *i*' being secured to the upper end of said stem, so that the shell or nozzle *h* may be rotated by turning said wheel.
- 10 Said hand-wheel is preferably provided with an arrow or other indicating device to indicate the position of the port *h*'. The diameter of the passage *a*' is somewhat less than the diameter of the shell *h*, so that when the latter is turned into the dotted position of Fig. 4 the ports *h*' and *h*² will both be entirely within the chamber *d*, the sides of said ports next the tub being approximately in the plane of the face of the ring *g*. The relative 15 diameter of the shell *h* and ring *g* and thickness of the wall *a* of the tub are such that a portion or segment of the sphere or shell *h* at all times protrudes into the tub beyond the inner surface of the walls *a*, as indicated in Figs. 2, 3, and 4. Said shell is held against the ring *g* by a head *k*, borne on the end of an adjusting-screw *m*, the latter being threaded into the wall of the chamber *d* and arranged so that its center line lies in the horizontal 20 plane through the center of the spherical shell *h*, so that the bridge *h*³ provides a bearing for the head *k* when the shell is in the position of Figs. 2 and 3.
- In practice water under pressure will be admitted to the chamber *d* and will fill the shell *h*, and when the shell is turned on its vertical axis, so that both its inlet and outlet ports are within the chamber *d* or the dotted position shown in Fig. 4, communication between the chamber *d* and the tub will be completely shut off, and the shell will be firmly pressed against the valve seat or ring *g* by the water, as well as held against it by the bearing *k*.
- If it is desired to wash out the tub, it is only necessary to turn the hand-wheel *i*' so that a portion or all of the port *h*' is brought into register with the passage *a*', causing a jet of water to be projected or forced into the tub. In this way the shell *h* will act as a nozzle as well as a valve, the jet of water being projected in a direction corresponding to the position in which the shell is rotated. By reason of the fact that the shell extends into the tub somewhat beyond the inner walls thereof it will be apparent that a jet of water may be projected through the port *h*' in a direction approximately parallel with the side walls of the tub in either direction and also in any intermediate direction, as indicated in Fig. 1.
- By making the inner end of passage *a*' flaring less obstruction is offered to the water as it is discharged along the walls of the tub than if the passage *a*' were of uniform diameter.

In practice the ports are of such size that a large volume of water may be quickly sup-

plied, and as the water is preferably supplied at a high pressure it will be delivered into the tub at a high velocity, varying somewhat according to the extent to which the port *h*' is opened.

By providing four nozzles *h* at the ends of the straight portions of the side walls of the tub a jet of water may be directed over every portion of the bottom of the tub, so that all of the pulp may be washed out of the tub without making the use of scrapers or other implements necessary. While washing out the tub one of the nozzles may be turned to direct a jet of water against the normal flow of the pulp, so that it will act as a temporary dam, and then the jet may be turned in the opposite direction, so as to suddenly release the accumulation, thereby causing the pulp to be swept along by the sudden rapid flow of water.

By opening each nozzle so as to direct a jet of water along the sides of the tub in the direction of the flow of the pulp the flow of the pulp may be accelerated adjacent the walls in proportion to the distance which it must travel in making a complete circuit of the tub. In this manner the grinding will be greatly facilitated and the necessity of frequent stirring be avoided. At the same time the pulp will be thoroughly washed by the constantly-incoming water, the excess of water being drained off through a screened overflow or outlet.

While the nozzles *h* protrude into the tub to some extent, their curved or spherical surfaces do not to any material degree obstruct the flow of the pulp or afford a place where the pulp may become lodged, so that the ordinary use of the tub is not interfered with in the least.

While I prefer a spherical form of nozzle or valve to one of cylindrical form on account of the fact that it is easier to form a water-tight seat for a spherical valve than one of cylindrical or other form, yet I consider such other forms within the spirit and scope of my invention.

Having thus described my invention, what I claim as new, and desire to secure by Letters Patent, is—

1. In combination with a tub of a pulp-beater having a passage in the wall thereof leading into the tub, said passage having a surrounding seat, a water-supplying nozzle engaging said seat and closing said passage except through its jet-orifice, and means for varying the horizontal position of said nozzle to direct a jet in different directions in the tub, substantially as described.

2. In combination with the tub of a pulp-beater having a passage in the wall thereof leading into the tub, said passage having a surrounding seat, a water-supplying nozzle engaging said seat and closing said passage completely in certain positions, and means permitting movement of said nozzle to bring its

- jet-orifice partly or wholly into register with said passage from either side thereof to permit a jet to be projected in different directions in the tub, substantially as described.
5. 3. In combination with the tub of a pulp-beater having a passage in the wall thereof leading into the tub, said passage having a surrounding seat, a water-supplying nozzle engaging said seat and closing said passage completely in certain positions, said nozzle having a jet-orifice of less width than said passage, and means for moving said nozzle horizontally to direct a jet in different directions from said passage, substantially as described.
10. 4. In combination with the tub of a pulp-beater having a passage in its wall, said passage having a surrounding seat, a valve engaging said seat and closing said passage in certain positions thereof, said valve having a curved portion projecting into the tub, and provided with a jet-orifice and means for swinging said valve horizontally and means for supplying water to said jet-orifice, substantially as described.
15. 5. In combination with the tub of a pulp-beater having a circular passage through its side wall, said passage having an encircling valve-seat, a spherical-faced valve engaging said seat and closing said passage, said valve having a jet-orifice through its face, means for swinging said valve horizontally to bring said orifice into register with said passage, and means for supplying water to said orifice, substantially as described.
20. 6. In combination with the tub of a pulp-beater having a circular passage through its side wall, said passage having an encircling valve-seat, a spherical-faced valve engaging said seat, closing said passage and projecting into the tub beyond the inner surface of said wall, a jet-orifice being formed through said face, means for swinging said valve horizontally to bring said orifice into register with said passage, and means for supplying water to said orifice, substantially as described.
25. 7. In combination with the tub of a pulp-beater having a circular passage in its side wall, said passage having an encircling valve-seat, a hollow spherical valve pressed against said seat, closing said passage, and extending beyond the inner surface of said wall, said valve having a jet-orifice of less width horizontally than the diameter of said passage, said orifice registering with said passage, in certain positions of said valve, means for rotating said valve about a vertical axis, and for supplying water to said orifice, substantially as described.
30. 8. In combination with the tub of a pulp-beater having a passage through its wall, a valve seated against the outer end of said passage, having a curved face, and a port formed through said face, a casing to which water under pressure may be supplied, inclosing said valve, and means for swinging said valve horizontally, substantially as described. 60
35. 9. In combination with the tub of a pulp-beater having a passage through its wall, a valve seated against the outer end of said passage, having a curved face, and a port formed through said face of less width horizontally than said passage, a casing to which water under pressure may be supplied, inclosing said valve, and means for swinging said valve horizontally, substantially as described. 65
40. 10. In combination with the tub of a pulp-beater having a passage through its wall, flaring at its inner end, a valve seated against the outer end of said passage, having a curved face, and a port formed through said face, a casing to which water under pressure may be supplied, inclosing said valve, and means for swinging said valve horizontally, substantially as described. 70
45. 11. In combination with the tub of a pulp-beater having a circular passage through its wall adjacent its bottom, a spherical hollow valve having oppositely-located inlet and outlet ports seated on the outer end of said passage and closing the same, a casing inclosing said valve and connected to the wall of the tub, and means for supplying water thereto, and means for rotating said valve consisting of a stem extending vertically through said casing and connected to said valve, substantially as described. 75
50. 12. In combination with the tub of a pulp-beater having a circular passage through its wall adjacent its bottom, a spherical hollow valve having oppositely-located inlet and outlet ports, seated on the outer end of said passage and closing the same, a casing inclosing said valve and connected to the wall of the tub and means for supplying water thereto, an adjustable bearing engaging the side of said valve opposite said passage and holding it against its seat, and means for rotating said valve on a vertical axis, substantially as described. 80
55. In testimony whereof I have signed my name to this specification in the presence of two subscribing witnesses. 85
